WEB TENSIONING MECHANISM

Albert J. Horton, White Plains, N. Y., assignor to
 R. Hoe & Co., Inc., New York, N. Y., a corporation of New York

Application May 1, 1936, Serial No. 77,308

18 Claims. (Cl. 242—75)

This invention relates to a web tensioning or feed control mechanism for use with machines operating upon a web and has especial reference to tensioning mechanism for the paper web running into printing machines of the high speed type.

In machines of this type, a web supply mechanism having a rotatable reel for supporting a plurality of web rolls is provided. The arrangement in the web supply mechanism is such, that when the web running into the machine from the running web roll is substantially removed from the roll, the reel is rotated to dispose a replacement web roll in position to have its web joined to the running web. While running at its original position, the tension of the running web may be governed by a web roll control mechanism which acts upon the roll through a driven endless belt, and which is controlled by a roller disposed in a loop in the web, as it runs into the machine. The roller is generally supported upon arms, which upon swinging due to the lengthening of the web loop upon a decrease in web tension, or the shortening thereof due to an increase in web tension, causes the actuation of mechanism provided to compensate for these differences in tension and maintain the web tension substantially uniform. Mechanism similar to that shown herein for maintaining the tension of a web running from a roll, by the use of an endless driven belt, is shown and fully described in Patent 2,155,430.

Under certain conditions, it is desirable to vary or regulate the tension on the web running into the machine and this may be accomplished by the provision of a counterweight which is adjustable along an arm connected to the arm supporting the roller disposed in the web loop. To avoid abrupt movement of the roller supporting arm should the machine be suddenly stopped or if the running web should break, a dash pot may be provided in connection with the roller supporting arm. Mechanism as referred to above, wherein an adjustable counterweight is used and a dash pot is provided, is shown and fully described in Patent Number 1,881,589, dated October 11, 1932.

When the running web roll approaches exhaustion and the lead of the web is to be changed to draw paper from a replacement roll, the running roll is moved out of contact with the belt and it is, therefore, necessary to provide a device for maintaining the required tension on the web as it continues to run from the roll. A manually adjustable brake device acting directly upon the spindle carrying the roll is in use and

has proven satisfactory in most instances, but is inconvenient in some respects, as it requires attention and occasional adjustment, as changes in roll diameter cause variations in the web tension.

This invention contemplates, as its principal object, the provision of a web tensioning mechanism which is controlled by a roller disposed in a loop of the web as it runs into the machine and which will automatically maintain the tension of the web substantially uniform when the running web roll is in any of its reel supported positions.

Another object is to provide a web tensioning mechanism controlled by a roller running in a loop in the web and which, while under such control, acts directly upon the web to compensate for variations in the tension thereof.

Still another object is to provide in a web tensioning mechanism adapted to produce a drag on the web a driven roller over which the web runs and means to press the web against the driven roller with varying degrees of pressure under the control of the tension on the running web.

It is also an object of the invention to provide a web tensioning mechanism of generally improved construction, whereby the device will be simple, durable and inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed.

The preferred embodiment of the invention is illustrated in the accompanying drawings, wherein:

Figure 1 is a side view of a web supply mechanism for a printing machine, with a web tensioning mechanism, constructed in accordance with the principles of this invention, applied thereto;

Figure 2 is an enlarged side view of a portion of the mechanism shown in Figure 1;

Figure 3 is a face view of the mechanism shown in Figure 2 looking in the direction of arrow 3 thereof; and

Figure 4 is a diagram showing the control circuits of the tension controlling motor.

The web supply mechanism shown in the drawings is of the type referred to above, wherein a rotatably mounted reel 11 is provided, having provision in the form of arms 12, 13 and 14 for sup-

porting an expiring web roll 15, a replacement web roll 16, and a spare roll 17. There is also provided a driven belt 18 led about pulleys 19, 21 and 22, the pulley 22 being mounted upon the end of arms 23 secured to a rockable shaft 24, and the pulley 19 being drivingly connected to a shaft 25 by bevel gears 26 and 27. The shaft 25 may be drivingly connected with a driven part of the machine and arranged to drive the belt 18 preferably at a speed slightly less than that of the web 28 running into the machine. A gear segment 29 secured to the shaft 24 has a pinion 31 in mesh therewith, the pinion 31 being secured upon the shaft of a motor 32. Suitable control mechanism for operating the motor in either direction, is enclosed in a casing 33, and is arranged to be actuated by a reciprocable rod 34, slideable in response to variations in the tension of the running web 28, by being connected to and movable with arms 35, which are secured to a shaft 35' rotatably supported in fixed bearings. The arms 35 support a roller 36 disposed in a loop of the running web.

The roller 36 may be counterbalanced by a weight 37 slidably mounted upon a rod 38 and adapted by means of tongues 39 to be positively located in various positions along another arm 41 secured to the shaft 35' and movable with the arms 35, the tongues 39 engaging in notches 42 formed in the arm 41. A spring 43, secured at one end to a machine frame part 44, reacts against the arms 35 through connection therewith by means of another arm 45, which is connected with the other end of the spring 43 and an arm 35, and constantly tends to urge the roller 36 away from the web 28. The arrangement is such that the combined action of the roller 36, the weight 37, and the spring 43 will impose a sufficient pull upon the web to maintain it taut, and under the desired tension.

Electrical connections for controlling the motor 32 by means of the control switches mounted within the casing 33 are shown in Figure 4, and it will be understood that an excess of tension on the web running to the machine will raise the roller 36 and move the rod 34 towards the right, whereupon switch 81 will be swung to make connection with contact 82, thereby closing a circuit that may be traced from line L1 through conductor 83, solenoid 84, conductor 85 to contact 82, through switch 81 and conductor 86 to line L2, thus energizing solenoid 84 and establishing a circuit through motor 32, that may be traced from L1 through conductor 83, switch 87 (then closed), and conductors 88 and 89 to the motor 32 and from the motor by conductors 91 and 92, through switch 93, through conductors 94 and 86 to L2, and assuming the motor 32 to be a three-phase alternating current motor, line L3 will be connected directly to the motor by conductor 95. Thus energizing the motor will cause it to rotate in a direction to decrease the wrap of the belt 18 about the roll 16, and thereby reduce the tension on the web running to the machine.

Should the tension on the web become insufficient, the floating roller 36 will descend, thereby moving the arm 34 to the left and closing the switch 96. This will energize the solenoid 97 and complete a circuit that will cause the motor to rotate in the opposite direction and thereby increase the wrap of the belt 18 about the roll 16 and impose additional drag on the roll, thereby increasing the tension on

the web. Circuits thus established may be traced from L1 through conductor 83 to solenoid 87 and thence conductor 88 to contact 99 and through switch 96 and conductor 86 to line L2. Solenoid 97 thus being energized, the switches 101 and 102 will be closed, establishing a circuit to the motor, that may be traced from line L1, switch 101 and conductors 92 and 91 to the motor 32, and from the motor by conductors 89 and 88, through switch 102 which is connected to line L2. When the correct tension is being applied to the web, neither switch 81 or 96 is closed and the rotor of the motor 32 remains stationary.

By means of the above described mechanism, the tension on a web running from a roll disposed in the position of roll 16, will be maintained substantially uniform, the belt arm 23 being swung by the motor 32 under control of the mechanism in the casing 33 to increase or decrease the wrap of the belt 18 about the roll 16, and restrain or permit freer rotation of the roll in response to movement of the floating roller. A dash pot, not shown, may be provided in accordance with the construction shown in the patent above referred to, if so desired, to prevent abrupt movement of the arm 35. When the roll 16 is nearly exhausted, the reel 14 is rotated to position the rolls 15 and 16, as shown in Figure 1, wherein the roll 16 now becomes the replacement roll and the roll 15 is the roll from which the web is expiring. The belt 18 now acts by engagement with the replacement roll to bring it up to web speed, whereupon a web deflector or brush 46 may be actuated in a known manner to press the web against the roll 16 to join it by means of adhesive to the web thereof.

When the roll 15 is moved out of control of the belt 18, the tension on the web may be controlled by a manually actuated device acting upon a spindle 47 engaging the core of the web roll and which is herein shown as being constituted by a brake band 48 in frictional engagement about and with a brake drum 49 secured to the spindle 47. By means of an adjusting wheel 51, the amount of braking friction may be controlled so that the desired web tension may be substantially maintained while a replacement roll is being brought into position and its web joined to the running web 28.

Although the mechanism about to be described is primarily intended to automatically maintain the tension on the web running from a web expiring roll 15 positioned as shown, it also may be in operation to assist the belt 18 in maintaining a uniform tension on a web running from the roll 16. It will also efficiently operate in cooperation with the manually adjustable tension device above described and will efficiently maintain a substantially uniform tension on the running web without either the belt 18 or the manually adjustable tension device being in use. Herein the web tensioning mechanism embodying the features of this invention includes arms 52 (see Figures 2 and 3) secured to the shaft 35' and movable with the arms 35, each arm 52 having a cam roller 53 carried by its free end, and which is disposed in a cam slot 54 formed in the free end of each of a pair of levers 55 pivoted at their other ends by being rotatable on a shaft 56 journaled in bearings 50 secured to the brackets 57, the cam slots 54 being formed to cause rocking of the levers 55, 75

when the arms 52 are swung with the arms 38, under influence of the web 18 upon the roller 36.

The web 28 from either the replacement roll 5 or the expiring web roll 15 is directed into the machine by being led over roller 58, under roller 59, over roller 60, looped under the roller 36, and thence over the rollers 61 and 61' and to the machine. As the web passes over the roller 58, it is engaged by a roller 62. The roller 58 is driven at a speed slightly less than that of the running web, by being drivingly connected to the shaft 25 for instance, by means of sprockets 63 and 64 respectively connected to shaft 65 of the roller 58 and shaft 66 of the pulley 19, which is connected to the shaft 25 through the bevel gears 26 and 27. A chain 67 connects the sprockets 63 and 64. The roller 62 is mounted for free rotation upon the outer end of arms 68, which are supported on and suitably secured to the shaft 56. Springs 69 each connected at one end to an arm 68 and at its other end with a lever 55 connect these parts, whereby movement of the levers 55 upwardly will pull the roller 62 through the springs 69 away from the roller 58 and release pressure thereof against the web 28 running over the roller 58 and permit the web to slip; and movement of the levers 55 in the other direction will permit the roller 62, due to its weight, to press the web 28 into firmer contact with the roller 58 and impose increased tension on the web by tending to retard its speed.

The roller 62 is preferably made of a non-metallic material, such as rubber, to reduce the noise of its engagement at high speed, with the roller 58, and the springs 69 may act as a resilient connection between the arm 68 and lever 55 to cause the movements of the roller 62 to be damped. An arm 71, having a handle 72 secured thereto is pivoted on a screw stud 73, secured to one of the arms 68 and in axial alignment with the roller 62. The arm 71 is adapted to be rocked by the handle 72 into the position shown in dotted lines in Figure 2 whereby its cam end 74 will rest upon the extended end 75 (see Figure 3) of the roller 58 disposed beneath the same, and separate the roller 62 from the roller 58, for the purpose of threading a web therebetween and into the machine when the machine is stopped. Upon starting the machine, the roller 58 is rotated, the arm 71 rides off the extended end 75 of the roller and allows the roller 62 to engage the web on the roller 58, and due to the weight of the handle 72, swings into the full line position, shown in Figure 2. If desired the cam 74 may be arranged to engage the shaft of the roller 58 instead of its periphery or it may engage a separate wheel rotated with the shaft. By the provision of the above described web tensioning mechanism, the tension on the web 28 will be maintained substantially uniform during the interval the web roll 15 is out of engagement with the belt 18, when preparing and disposing the web supply mechanism in readiness for joining a running web to the web of a replacement roll. When a web tensioning mechanism of the above nature is in operation in conjunction with the belt 18, that is, when a web is running from a roll positioned at 16, it acts as an auxiliary web tensioning device assisting the belt 18 and its controls, to maintain the web tension uniform. The manually adjustable tensioning device, above described, may be used to advantage with the web tensioning mechanism

of this invention. This is accomplished by setting the manually adjustable device to impose the required friction upon the roll 15, when the web is practically exhausted therefrom, whereupon the action of the rollers 58 and 62 upon the web 28 need compensate only for variations in web tension occurring while the web, remaining on the roll 15 after its removal from the influence of the belt 18, is running off from the roll. Should occasion arise, where the use of a belt 18 and the manually adjustable tensioning device, both of which act upon the roll, are dispensed with, the web tensioning mechanism of this invention, which acts directly upon the running web, is capable of efficiently maintaining the tension on the running web substantially uniform.

It will be understood that the invention may be embodied in other specific forms without departing from the spirit or essential attributes thereof, and it is therefore desired that the present embodiment be considered in all respects as illustrative and not restrictive, and it will be further understood that each and every novel feature and combination present in or possessed by the mechanism herein disclosed forms a part of the invention included in this application.

What I claim is:

1. In a web tensioning mechanism, a roller against which a running web is led, means to drive said roller at a speed slightly less than the speed of the running web and in a direction to feed the web in the same direction as the web is running, a swingable roller arranged to engage the running web and press it against said driven roller whereby a drag will be imposed by the driven roller upon the web, and means influenced by variations in the web tension to control the swinging of said swingable roller to vary the degree of pressure imposed thereby and the drag of the driven roller upon the web.

2. In a web tensioning mechanism for a machine operating upon a web and into which the web is being drawn, a roller driven slower than the speed of the web and against which the web is led and over which it may slip, a second roller disposed in a loop of the web to be moved thereby under influence of variations in web tension, and means actuated by the movement of the second roller to cause the running web to engage the driven roll at the degree of pressure required to impose a braking action of the driven roller upon the web to maintain the web tension substantially uniform.

3. In a mechanism for controlling the tension of a running web, a first member driven to move in the direction of, and at slightly less speed than that of the running web, a second member arranged to press the web against said first member to cause a drag to be imposed upon the web by said first member, and means influenced by variations in web tension to vary the degree of pressure imposed on the web by said second member.

4. In a web tensioning mechanism, cooperating rollers between which a running web is disposed, the first of said rollers being driven at slightly less speed than that of the running web, said driven roller being driven to rotate in a direction to feed the web in the same direction that it is running, the second of said rollers being movable to press the running web against the first roller to cause a drag to be imposed on the web, and means influenced by variations in tension of the web after it has passed said rollers

to move said second roller and vary the drag imposed on the web.

5. In a web tensioning mechanism, a first rotatable member disposed in a loop in a running 5 web and movable in response to variations in the web tension, a second rotatable member over which the web runs and against which it is pressed to impose a braking effect on the web, and means actuated by movement of said first 10 member to vary the degree of pressure of the web on said second member.

6. In a tension control mechanism for a web being drawn from a web roll into a machine that operates upon the web, a pair of rollers between 15 which the web is pressed, movable bearings for one of said rollers, means for driving one of the rollers at a peripheral speed somewhat slower than the speed of the web to impose a drag thereon, a floating roller running in a loop in 20 the web, and means connecting the floating roller with the movable bearings, whereby bodily movement of the floating roller will vary the drag on the web.

7. In a tension control mechanism for a web 25 being drawn into a machine whereby it is operated upon, a pair of rollers between which the web is pressed, movable bearings for one of the said rollers, means for driving one of the rollers in timed relation with the machine and at a peripheral speed somewhat slower than the speed 30 of the web to adapt it to impose a drag thereon, a floating roller running in a loop in the web, and means connecting the floating roller and the movable bearings, whereby any movement of the floating roller due to variation in the length of 35 the loop will simultaneously vary the pressure of the said pair of rollers against the web and the resulting drag thereon.

8. In a tension control mechanism for a web 40 being fed to a machine whereby it is operated upon, a first roller and a second roller between which the web is normally pressed, means for driving the first roller in timed relation with the machine, movable bearings for the second roller 45 whereby it may be moved away from the first roller, a cam operably connected to the second roller and adapted to engage the first roller, the said cam being movable to hold said rollers separated when they are not rotating and rendered 50 ineffective to maintain the separation, when the first roller starts to rotate.

9. In a web feed control mechanism for a web being fed to a machine by which it is operated upon, a first roller and a second roller between 55 which the web is normally pressed, means for driving the first roller in timed relation with the machine, a movable support for the second roller whereby it may be spaced from the first roller to facilitate threading a web therebetween, an 60 engaging surface rotating with the first roller, and a separating element operably connected to the movable support and adapted to engage the engaging surface; the said separating element being movable to hold said rollers separated when 65 they are not rotating and automatically rendered ineffective to maintain the separation, when the first roller starts to rotate.

10. In a web feed control mechanism for a web being fed to a machine by which it is operated upon, a pair of rollers between which the web is normally pressed, means for driving one of the rollers in timed relation with the machine, a movable support for one of the rollers whereby it may be spaced from the other roller to facilitate threading a web between them, and a sepa- 70

rating element movable to operative position to space one of the rollers from the other roller; said separating element being automatically movable to inoperative position when the machine starts. 5

11. In a mechanism for controlling the tension of a web running from a web roll mounted upon a rotatable supporting spindle, a manually controlled brake on said spindle adapted to apply a braking action thereon to cause a drag on the running web, a first rotatable member driven at less speed than that of the running web, said driven rotatable member rotating in a direction to feed the web in the same direction that it is running, a second member movable to engage and press the web against the first member to cause a drag to be imposed on the running web, and means influenced by variations in the tension of the running web after it passes said first member to vary the degree of pressure imposed upon said web by said second member. 20

12. In a web tension device for a machine operating upon a web running from a web roll, in combination, a driven belt engaging the periphery of the web roll and constituting a brake for said roll, a driven roller over which the web 25 is led after it leaves said roll, said driven roller rotating in a direction to feed the web in the same direction that the web is running, said belt and said roller being driven at slightly less speed than that of the web, means to vary the wrap 30 of said belt about said web roll, means to press the web against said roller, and a roller running in a loop in the web adapted to vary the web pressing movement of said web pressing means, to maintain substantially constant tension on 35 the web running into the machine.

13. In mechanism for controlling the tension of a running web, a rotatable member over which the web runs and which is driven at less speed than the running web, said rotatable member 40 rotating in a direction to feed the web in the same direction that it is running, a movable member arranged to press the web against the rotatable member to cause a drag to be imposed upon the web by said rotatable member, and 45 means actuated by variations in web tension to move said movable member.

14. In a web tension mechanism for a machine operating upon a web drawn from a roll and in which running web rolls are successively moved 50 from a normal running position to an exhausting position preparatory to joining the web of an expiring roll to the web of a replacement roll without stopping the machine, in combination, means for rotatably supporting a plurality of 55 web rolls that are moved successively to running and exhausting positions, a first braking means operable on a web roll in running position to control tension on the web running therefrom, a second braking means operable directly on the 60 web running from a web roll that has been moved to exhausting position, a floating roller running in a loop in the web, and means operably connecting the floating roller with the first braking means and the second braking means 65 to automatically maintain a desired web tension.

15. In a web tensioning mechanism for a machine operating upon a web running from a web roll, in combination, a roller driven at a speed less than that of the running web, said driven 70 roller having the web in contact therewith and rotating in a direction to feed the web in the same direction as the web is running, a freely rotatable roller arranged to press the running web against the driven roller, a driven belt mov- 75

- ing at a speed less than the peripheral speed of said web roll and engaging the web roll to cause a braking action thereon, means to vary the wrap of the belt upon the web roll to vary its braking action, and means influenced by variations in the tension of the running web to vary the degree of pressure imposed upon the running web by the freely rotatable roller.
16. In a web tensioning mechanism for a machine operating upon a web running from a web roll, in combination, a roller driven at less speed than the web over which the web is led and may slip, a freely rotatable roller arranged to press the running web against the driven roller to apply a drag on the web, a manually adjustable friction applying device acting on the web roll to cause tension on the web running therefrom, and means influenced by variations in the tension on the web to actuate said freely rotatable roller to vary the degree of drag imposed on the running web by said driven roller.
17. In a web tension control device for a machine operating upon a web running from a web roll, in combination, a driven belt moving at a speed less than the peripheral speed of said web roll and engaging the web roll, means to vary the wrap of said belt upon the roll to control the tension of the running web, a roller driven at less speed than the running web and over which the web is led as it leaves the web roll, said driven roller having the web in contact therewith and rotating in a direction to feed the web in the same direction as the web is running, a second roller arranged to press the web against said driven roller, means to vary the degree of pressure imposed by said second roller upon the running web to control the tension thereof, and means influenced by the tension of the web as it enters said machine to actuate one of the aforesaid tension controlling means.
18. In a web tensioning mechanism, a roller around which a running web is led and driven at less speed than the running web, a swingable roller arranged to press the running web against said driven roller, means influenced by variations in the tension on the running web to vary the degree of pressure imposed by said swingable roller upon the web, and means movable in one direction into position to separate and hold said rollers separated when said web is stopped and arranged to move into another position to permit the rollers to move together when the web is started.

ALBERT J. HORTON.
